UNITED STATES PATENT OFFICE.

JOHN KING, OF ANSONIA, CONNECTICUT, ASSIGNOR TO ROBERT BUTTERWORTH, OF TRENTON, NEW JERSEY.

CIDER-MILL PRESS.

SPECIFICATION forming part of Letters Patent No. 239,174, dated March 22, 1881.

Application filed February 4, 1881. (No model.)

To all whom it may concern:

Be it known that I, JOHN KING, of Ansonia, in the county of New Haven and State of Connecticut, have invented a new Improvement in Cider-Mill Presses; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of the bed of the press; Figs. 2 and 3, longitudinal sections to illustrate the invention; Fig. 4, top view 15 of the press with the platen removed; Fig. 5, the platen inverted.

This invention relates to an improvement in that class of cider-presses in which the bed is constructed or arranged so that the pomace 20 may be placed in the hoop set at the end of the bed and then moved to bring it beneath the press, the object being to make the bed stationary and the platen on which the hoop and pomace are placed movable thereon, whereby greater stability or firmness of the press is had than when the bed itself is movable; and the invention consists in the construction, 25 as hereinafter described, and particularly recited in the claims.

30 A represents the bed of the press, which is of more than twice the length required for the operation of pressing. It is formed with an upwardly-projecting edge, to serve as guides for the juice to the exit a. Longitudinally on the bed are guides B, distant from each other the width of the platen C, and so that the platen placed between them, as in Fig. 1, may be moved longitudinally on the bed between the guides B B.

40 D is a rack or series of holes or notches at the end of the bed, opposite where the pressing is done, and extending about one-half the length of the bed.

The platen C is provided with wheels b b 45 d d at the opposite end, those at one end being nearer the outer edge than the other, so that those at one end do not track with those at the other end, or may be otherwise arranged so that the wheels do not track.

50 At the pressing end of the bed cavities b' b'

d' d' are made, corresponding to the wheels on the platen, and so that when the wheels enter those recesses the platen will drop flat upon the bed and be supported entirely by the bed. These recesses are, therefore, made at points 55 corresponding to the position of the wheels when the platen is in the proper position and beneath the pressing devices. This completes the construction.

The operation is as follows: The platen C 60 is placed upon the bed at the end opposite the pressing apparatus—that is, over the notches D, as seen in Fig. 3. On this the hoop is placed and filled with the pomace in the usual manner. Then the workman applies a crow 65 or other lever, the end of which engages in one of the notches D beneath the platen, and, raising the lever, moves the platen with its load toward the opposite end, thus gradually moving it until the wheels drop into their recesses and the platen takes its bearing upon the bed. Then the pressing is performed in the usual manner, and while the pressing is going on a second platen is arranged on the bed, as before described for the platen C, and loaded 70 with the pomace in like manner. When the pressing is finished the cheese is removed, also the platen. Then the second platen is moved forward, as described for the first, and the first platen carried to the other end and placed 75 upon the bed, as before. By this arrangement the only power required for moving the pomace to the press is that which is required to move the platen on its wheels; whereas when the bed is made movable nearly double the power 80 is required, because the bed has the load of the pomace and the cheese. Again, this construction has the advantage that the bed is an immovable part of the press, and hence is equally as strong and firm as a press having 85 a bed only of sufficient size to receive the pomace directly within it.

From the foregoing it will be understood that I do not broadly claim a cider-mill press constructed so that the pomace may be placed 90 in the hoop at a point one side of the pressing-platen and then moved beneath the platen to be pressed.

I claim—

1. The combination of the stationary double- 95

length bed of a cider-press with a platen of single length movable thereon between guides, so as to be transferred from one end to the other of said stationary bed, substantially as described.

2. The combination of the stationary bed of a cider-press with a platen movable thereon between guides, so as to be transferred from one end to the other, the said platen provided with wheels at both ends, those at one end out of the track of those at the other end, and depressions in the bed corresponding to said wheels at the point where the platen is to stand for the pressing operation, and so that

the platen will take its bearing on the bed independent of the wheels, substantially as described.

3. The combination of the stationary bed of a cider-press with a platen movable thereon between guides, so as to be transferred from one end to the other, and a series of recesses or notches in the bed in a longitudinal line, substantially as and for the purpose described.

JOHN KING.
